2 Sheets-Sheet 2

UNITED STATES PATENT OFFICE.

CHARLES KILNER, OF GREENVILLE, PENNSYLVANIA, ASSIGNOR TO WINE RAILWAY APPLIANCE COMPANY, OF TOLEDO, OHIO, A CORPORATION OF OHIO.

CAR-DOOR MECHANISM.

Application filed July 29, 1924. Serial No. 728,909.

To all whom it may concern:

Be it known that I, CHARLES KILNER, a citizen of the United States, residing at Greenville, in the county of Mercer and 5 State of Pennsylvania, have invented certain new and useful Improvements in Car-Door Mechanism, of which the following is a specification.

10 My invention relates to car door mechanism and particularly to such as is applicable to the drop doors of hopper cars.

The principal object of the invention is 15 to provide simple and efficient means for swinging the drop door of a railway car to closed position and for releasing the door locking devices so as to permit the door to open.

At the present time railway cars having 20 drop bottom doors are largely equipped with door locking mechanism comprising a pivoted hook carried by the car body and adapted to cooperate with a door arm or hook seat mounted on the door. While door locking mechanism of this type is accessible 25 and capable of being easily operated under most circumstances, conditions and structures adjacent the railway tracks at points where the cars are loaded or unloaded sometimes render the operations of unlock- 30 ing and closing the doors inconvenient or difficult to perform. Such a condition is encountered where the car door must be actuated while the car is standing on a track beside an elevated platform extending 35 a considerable distance above the rails. By my invention mechanism is provided for easily and conveniently releasing and closing the car doors under such circumstances.

A primary feature of the invention consists, generally stated, in pivotally mounting 40 on the body of the car a hook adapted to have locking engagement with an outwardly projecting arm or seat carried by the door, the said hook being so constructed and combined with a door arm as to be capable of 45 being moved to unlocked position through the instrumentality of a device which may be manipulated by an operator from a position at a considerable height above the track, and the said operating device also being 50 adapted to engage the door and a portion of the car body so as to enable the door to be closed by the operator in such elevated position.

A further feature of the invention consists in providing the car body, car door and door locking device with suitable means adapting them for cooperation with a jointed operating device which may be employed by the operator both for releasing 60 the door and closing the same.

A further and more specific feature of the invention consists in the provision of a door operating device involving pivotally connected parts adapted to swing or rotate 65 with respect to each other in effecting a closing of the car door and one of which is adapted to serve as a lever for actuating the hook by which the door is normally maintained in closed position. 70

Other features of the invention residing in particular combinations of parts and in advantageous details of construction will hereinafter appear.

In the drawings illustrating the preferred 75 embodiment of the invention, the scope whereof is pointed out in the claims:

Figure 1 is a side elevation of a portion of the hopper of a railway car, the door thereof being locked in closed position and 80 the door operating device being shown in proper relation thereto for releasing the door supporting hook.

Figure 2 is an elevational view of the 85 construction shown in Figure 1, looking longitudinally of the car.

Figure 3 is a plan view of the door operating device shown in Figures 1 and 2.

Figure 4 is a side elevational view of the 90 devices illustrated in Figure 1 but showing the door in open position and the door operating device properly associated therewith for effecting a closing movement thereof, and also showing, in dotted lines, the position assumed by the door operating device 95 when the door has been shut.

Figure 5 is a diagrammatic view of a 100 railway car equipped with door mechanism embodying the invention, the said car being illustrated as standing on track between elevated platforms A and associated third rails B such as are frequently encountered at steel mills, and the door operating mechanism being illustrated in the position it occupies when it is employed for unlocking 105 the doors.

In the preferred form of the invention illustrated in the drawings, 1 indicates the

side sheet of a car hopper and 2 is a swinging door of the usual or any approved form for closing the hopper discharge opening. Rigidly mounted upon the outer side of the door, as by means of rivets 3, is a door arm 4 which projects outwardly beyond the side of the hopper side sheet 1. Where, as is the case illustrated in the drawings, the door is provided with a door stiffener or door spreader 5 the door arm 4 is preferably connected, as by means of rivets 6, to that member also. The door arm 4, which may conveniently be of angle iron formed so as to provide a seat or ledge 7 for cooperating with the door supporting hook to maintain the door in closed position, projects laterally outwardly beyond the said hook a sufficient distance to form a bearing point or fulcrum 8 for the lever or bar 9 of the door operating device when the latter is manipulated for the purpose of rotating the door supporting hook to unlocked position.

The hook 10 for cooperating with the door arm 4 is pivotally mounted at 11 upon the side sheet 1 of the hopper and preferably swings in parallel relation thereto. The well known locking cam 12, pivoted to the car body at 13, may, if desired, be employed to retain the hook in locked position. The hook is provided with a seat or ledge 14 for overlappingly engaging the flange 7 of the door arm 4 when the door is closed and it is also formed with a shoulder 15 which, when the door is in said closed position, is spaced from the lower flange 16 of the door arm a sufficient distance to enable the laterally projecting lug or bent end 17 of the lever member 9 to extend between said door arm and hook so as to engage the shoulder 15 of the latter while the lever bears upon the upper edge or fulcrum point 8 of the door arm 4.

Pivotedly connected to the end of the bar 9 opposite that from which the lug 17 projects is a member 18 which is capable of being detachably connected to the car body so as to furnish a movable or swinging fulcrum for the lever 9 when the latter is employed in closing the door 2. A convenient means of suitably connecting the member 18 to the car body is to provide the side sheet 1 of the hopper near its lower end with an opening 19 which is adapted to receive a hook or projection 20 formed on the free end of the swinging fulcrum member 18. The pivotal connection between the members 9 and 18 of the door operating device is preferably accomplished by forming the member 18 with a pair of perforated spaced jaws 21 which receive between them the bar 9 and through which as well as through said bar a pivot bolt 22 passes. Encircling the pivot bolt and interposed between the bar 9 and one of the jaw members 21 of the member 18 is a spring washer 23 which

presses firmly upon the parts between which it is interposed so as to subject them to frictional resistance enabling the extension 18 to remain in a position permitting its hook 20 to be readily inserted in the opening 19 of the side sheet 1 of the hopper. When, as shown in Figure 4, the operating device is to be employed for closing the door 2, the lever bar 9 is positioned so as to pass beneath and engage the outer edge of the flange 16 of the door arm 4, while its lower end cooperates with the movable fulcrum formed by the pivot bolt 22 which attaches the lever to the swinging extension 18 movably connected to the car body. When thus positioned the lever 9 of the operating device may be forced toward the car hopper so as to move the door to closed position, as indicated in dotted lines in Figure 4.

It is obvious that each car might be permanently equipped with a door operating mechanism of the character described, but it is preferred to so construct the device that it is capable of being readily detached from the car, since this requires but a single one of these appliances to be kept at a loading or unloading point. It is also obvious that the mechanism herein disclosed may be modified in various details of construction without departing from the spirit of the invention.

I claim:

1. In car door mechanism, the combination with a drop door, of door supporting means operatively interposed between and movable with respect to said door and the car body for retaining said door in closed position, the car body being provided with means adapted to establish operative connection with a movable fulcrum member which is movably connected to a lever adapted to engage said door to effect a closing movement of the latter.

2. In car door mechanism, the combination with a drop door, of door supporting means operatively interposed between and movable with respect to said door and the car body for retaining said door in closed position, the car body being provided with means whereby a movable fulcrum member may be detachably and pivotally connected thereto, and the said door being provided with means adapted to engage a lever which is pivotally connected to said fulcrum member and in conjunction with the latter serves as means for effecting a closing movement of said door.

3. In car door mechanism, the combination with a drop door, of door supporting means operatively interposed between and movable with respect to said door and the car body for retaining said door in closed position, the car body being provided with means for forming an operative connection with a door operating device involving a

- plurality of relatively movably connected parts, one of said parts being formed as a lever adapted to engage said door, and the other of said parts being operatively interposed between said lever and the car body and being adapted to form a fulcrum for said lever.
4. In car door mechanism, the combination with a drop door, of door supporting means operatively interposed between and movable with respect to said door and the car body for retaining said door in closed position, the car body being provided with means for forming a detachable connection with door operating means adapted to effect a closing movement of said door, the said door operating means involving pivotally connected members, and a friction device for preventing free pivotal movement thereof, and one of said members being adapted to engage said door and to constitute a lever for cooperating therewith to effect a closing movement thereof.
5. In car door mechanism, the combination with a drop door provided with a door arm projecting outwardly beyond the neighboring portion of the car body, of a door supporting hook pivotally mounted on the car body and adapted to engage said arm to retain said door in closed position, the car body being provided with means adapted to form a movable connection with a movable fulcrum member which is operatively connected to a relatively movable lever adapted to engage said door arm for the purpose of effecting a closing movement of the door.
6. In a car door mechanism, the combination with a drop door, of door supporting means operatively interposed between and movable with respect to said door and the car body for retaining said door in closed position, a fulcrum member movably supported on the car body, and a lever movably connected to said fulcrum member, said lever being adapted to engage said door to force the latter to closed position.
7. In a car door mechanism, the combination with a drop door provided with outwardly projecting means adapted to form a seat to be engaged by a door retaining hook for the purpose of supporting said door in closed position, of a hook pivotally mounted upon the car body and provided with a ledge for cooperating with said seat to retain the door in closed position, said hook being provided on its under face with a shoulder adapted to cooperate with a portion of a door operating lever when the latter is caused to fulcrum upon said projecting means to effect an unlocking rotation of said hook.
8. A lever mechanism adapted to be detachably associated with a car having a drop bottom door and to serve as a means for moving said door to closed position, said mechanism involving a rigid bar adapted to engage the car door, and a member pivotally connected thereto and adapted to be detachably connected to the car body.
9. A lever mechanism adapted to be detachably associated with a car having a drop bottom door and to serve as a means for moving said door to closed position, said lever mechanism comprising a rigid bar adapted to engage the car door, a member pivotally connected to said bar and adapted to detachably engage the car body, and means operatively interposed between said last named member and said bar for controlling the relative pivotal movements thereof.
10. A lever mechanism adapted to be detachably associated with a car having a drop bottom door and to serve as a means for moving said door to closed position, said lever mechanism involving a rigid bar adapted to form a lever for cooperating with the door to force the door to closed position, a member pivotally connected to said bar and provided with a hook adapted to engage a portion of the car body to form a detachable connection therewith, and a friction washer interposed between said last named member and said bar.
11. A lever mechanism adapted to be detachably associated with a car having a drop bottom door and to serve as a means for moving said door to closed position, said door being adapted to be retained in closed position by door supporting means operatively interposed between and movable with respect to the door and the car body, said lever mechanism involving a plurality of relatively movable members one of which is adapted to form a detachable connection with the car body and one of which is adapted to engage said door supporting means to move the latter to a position permitting said door to open.
12. In a car door mechanism, the combination with a drop door provided with seat member adapted to be engaged by a door retaining hook for holding said door in closed position, of a hook pivotally mounted upon the car body and provided with a ledge for cooperating with said seat to retain the door in closed position, and a shoulder formed on the under face of said hook adapted to be engaged by a suitable lever to effect a movement of said hook about its pivot and thereby release said door.
13. In a car door mechanism, the combination with a drop door provided with seat member adapted to be engaged by a door retaining hook for holding said door in closed position, of a hook pivotally mounted upon the car body and provided with a ledge for cooperating with said seat to retain the door in closed position, and a projection on the under face of said hook adapt-

ed to be engaged by a suitable lever to effect a movement of said hook about its pivot and thereby release said door.

14. In a car door mechanism, the combination with a drop door provided with seat member adapted to be engaged by a door retaining hook for holding said door in closed position, of a hook pivotally mounted upon the car body and having its forward or free

end projected downwardly to form a ledge 10 for cooperating with said seat to retain the door in closed position, and a projection on the under face of the free end of said hook adapted to be engaged by a suitable lever 15 to effect an unlocking rotation of said hook.

In testimony whereof I affix my signature.

CHARLES KILNEB
